UNITED STATES PATENT OFFICE.

ELLSWORTH A. DEWEY, OF WASHINGTON, DISTRICT OF COLUMBIA.

EXCAVATING-MACHINE.

1,299,826.

Specification of Letters Patent.

Patented Apr. 8, 1919.

Application filed December 15, 1913. Serial No. 806,869.

To all whom it may concern:

Be it known that I, ELLSWORTH A. DEWEY, citizen of the United States, residing at Washington, in the District of Columbia, have invented certain new and useful Improvements in Excavating-Machines, of which the following is a specification, reference being had therein to the accompanying drawing.

10 This invention relates to improvements in excavating machines.

The invention aims to improve the construction of excavating machines and to provide an improved machine of this character for constructing drainage ditches, roadways, canals, levees and the like and capable of forming a trench or ditch with sloping side walls which will be substantially smooth and solid, and of removing all of 20 the loose material from the trench during the excavating operation.

The invention comprehends excavating instrumentalities including a rotary excavating wheel equipped with cutters at the 25 sides thereof to cut and shape the side walls of the ditch and an excavating conveyer operating centrally of the excavating wheel and serving to convey the loose material out of the ditch. An important novel feature 30 of the invention resides in the special construction and arrangement of the cutters at the sides of the excavating wheel whereby clogging is prevented, a clean even cut is obtained, and the cutters act to gradually feed 35 or force the material cut from the sides of the ditch to the bottom thereof in the path of the excavating conveyer.

Another object of the invention is to provide an improved machine of this character 40 which while of comparatively simple and light construction will possess great strength and durability.

A further object of the invention is to provide for adjustably supporting the excavator mechanism and for elevating and lowering the same with a minimum expenditure of power and without subjecting the supporting frame to extensive strains.

The invention, with its advantages and 50 the novel construction, combination, and arrangement of parts comprising the same will be understood from the following detailed description when considered in connection with the accompanying drawings 55 forming a part hereof and illustrating a preferred embodiment of the invention.

In the drawings:

Figure 1 is a side elevation of an excavating machine constructed in accordance with the present invention, some of the side cutters of the wheel being omitted for the sake of clearness. 60

Figs. 2 and 3 are plan views, these placed end to end constituting a plan of the whole of the front portion of the machine, with 65 certain parts omitted.

Fig. 4 is a rear elevation.

Fig. 5 is an enlarged detailed view of a portion of the excavating conveyer and the dumping mechanism for the conveyer 70 buckets.

Fig. 6 is a diagrammatic view illustrating the arrangement of the cutters.

Fig. 7 is a plan of one of the side cutters. 75

Fig. 7^a is a sectional view taken on the line 7—7 of Fig. 7.

Fig. 8 is an edge view of the same and its connecting means.

Fig. 9 is a side view of the cutter. 80

Fig. 9^a is a sectional view taken on the line 9—9 of Fig. 9.

Figs. 10 and 11 are a plan and side elevation respectively of the bucket filling plows.

Figs. 12, 13 and 14 are detail views of one 85 of the plows and the structure for connecting the same to the wheel.

Referring particularly to Figs. 1, 2, 3 and 4 of the drawings, the excavating instrumentalities and allied mechanism is carried by a 90 main frame 1, which is supported upon and between a pair of tractors 2 and 3 extending substantially throughout the entire length of the machine at opposite sides thereof. Each tractor comprises an elongated or substantially oblong frame 4 and an endless tractor apron 5. The tractor frames, which are preferably constructed of structural steel and braced and trussed as shown in the drawings, are provided at the bottom with longitudinal 95 downwardly facing channels 6 extending along opposite sides thereof, and along the top at opposite sides with longitudinal beams 7 which project beyond the tractor frame at the front and rear thereof. Each tractor 100 apron 5 is made up of a pair of spaced roller sprocket chains 8 of usual construction and transversely disposed tread bars or members 9 connecting the sprocket chains and secured thereto at the outer faces of the links of the 105 chain. The pairs of sprocket chains are arranged on front and rear pairs of sprocket 110

wheels 10 and 11 that are fixedly secured to shafts 12 and 13 mounted for rotation in suitable bearings secured to the under side of the front and rear projecting portions of the 5 longitudinal beams 7, the usual rollers (not shown) at the inner side of the sprocket chains running in the longitudinal downwardly facing channels 6 which thus serve as tracks for the lower runs of the chains. 10 The tractor aprons are adapted to be driven to advance the machine during the cutting or excavating operation and in transporting the machine from place to place. The tractor frames are rigidly connected at their 15 front ends by a plurality of superimposed transverse I-beams 16 resting upon and suitably secured to the longitudinal beams 7, bracing 19 between the I-beams 16 and the longitudinal beams 7 at the corners being 20 provided. The main frame 1 is shown in the drawings as substantially triangular in shape and consisting of spaced longitudinal side beams 20 and 21 and oppositely inclined upwardly extending front and rear beams 22 25 and 23 mounted upon the longitudinal side beams 20 and 21 and connected together in pairs at their upper ends by an upper transverse beam 24, the front beams 22 and the rear beams 23 being connected with each 30 other by bracing 23 as shown in Fig. 4 of the drawings. Mounted at intervals upon the transverse I-beams 16 are transversely alined bearing brackets 26 having spaced side portions and receiving a plurality of 35 alined pivots 27 upon which the front portion of the main frame 1 is mounted, the main frame being provided at points adjacent the lower ends of the front inclined beams 22 and 23 with bearings 28 fitting between the spaced sides of the bearing brackets 26 and provided with eyes or openings through which the transversely alined pivots 27 pass. The bearings 28 at the sides of the frame are secured to the longitudinal side 40 beams 20 and 21 at opposite sides thereof, the pivots 27 at these points passing through the said beams 20 and 21. By this construction the main frame is hinged to the transverse I-beams 16 to tilt or swing upwardly and 45 downwardly to arrange the excavating mechanism for regulating the depth of cut and also for elevating said mechanism clear of the ground in transporting the machine from place to place.

50 The tractor frames (see particularly Figs. 1 and 4 of the drawings) are equipped at their rear portions with oppositely disposed derricks composed of oppositely inclined front and rear bars 30 and 31 mounted at 55 their lower ends upon the inner side beams 7 of the tractor frames and suitably secured together at their upper ends and braced by laterally inclined members 32 mounted upon outer projecting portions 33 of the tractor 60 frames. The main frame 1 is adjustably sup-

ported at its rear end by cables 34 arranged at opposite sides of the frame and connected to lower sheave blocks 35 fastened to the main frame 1 and reeved around a plurality of sheaves of the lower sheave blocks 35 and 70 sheaves of upper sheave blocks 36, which are fastened at the top of the derricks, the cables being arranged in a plurality of runs or stretches and finally extending from the lower sheave blocks forwardly along the 75 main frame at opposite sides thereof to a pair of hoisting drums 37 controlled by means hereinafter described. The lower sheave blocks 35 are located substantially beneath the upper sheave blocks 36 being arranged slightly in rear of the vertical plane of the same, and the runs or stretches of the cables substantially coincide with the arc of movement of the main frame so that the lifting force is applied substantially directly 80 above the load to be raised, thus enabling the main frame to be suspended, and lifted and lowered with a minimum expenditure of power and without subjecting the supporting frame to extensive or destructive strains. 90

The main frame is provided at opposite sides with rollers 41 which engage members 42 of the derricks and serve to steady the main frame in its vertical adjustment.

The main frame carries at its rear end a 95 transversely disposed shaft or axle 38 having its terminals arranged in hangers 39 and said shaft supports a rotary excavating wheel 40 which extends across the rear portion of the main frame in the space between the 100 sides thereof. The hangers or bearings 39, to which the lower sheave blocks 35 are directly connected, are secured in any suitable manner to the rear ends of the longitudinal side beams 20, 21, at the lower faces thereof, 105 and the transverse shaft or axle 38 is fixedly secured in the hangers and forms a substantially rigid connection between the rear ends of the side longitudinal beams of the main frame. 110

The rotary excavator wheel 40 (see Fig. 4) has a central cylindrical portion or section and outwardly tapered or conical side portions. The wheel comprises in its construction spaced central annular rims 43, 115 central intermediate connecting bars 44 and outwardly converging cutter carrying bars 45 and 46, the cutter carrying bars 45 extending from the spaced central rims to the end hubs 47 while the cutter carrying bars 46, which are located intermediate the inner portions of the spaces between the cutter carrying bars 45, extend from the rims to intermediate transverse braces 52 that are located between the rims and the end hubs 120 and form substantially circular braces for the conical side portions of the wheel and brace the long cutter carrying bars 45 against lateral displacement. The open frame constituting the side portion of the wheel is 125 130

also connected by bracing and tension members 53 and 54 extending from a central hub 55 to the side portions of the wheel. The bracing members 53 extend from the central hub to the intermediate transverse braces 52, and the tension members 54, which are connected at their outer terminals adjacent the intersection of bars 44 and 46, consist of rods adjustable in length by turn buckles or the like. The end hubs 47 are connected with each other by longitudinal tension rods 56 which coat with the before mentioned tension members in placing the frame or supporting structure of the excavating wheel under proper tension, the connecting members, the cutter carrying bars, and the bracing members serving as compression elements, an open oppositely tapered wheel construction being provided which, while comparatively light possesses the required rigidity and strength. The central intermediate connecting bars or members 44, which are suitably secured near the inner ends of the cutter carrying bars are inwardly offset from the periphery of the rims to provide a central annular space therebetween for the operation of a series of buckets 48 of an endless excavator conveyer 49.

The cutter carrying bars 45 and 46 are equipped with cutters 57, which are adapted to pare or slice the earth in thin, narrow fragments or slices from the sloping or inclined side walls of the ditch and to feed or force the severed earth downwardly and inwardly to carry the same to the bottom of the ditch in the path of the buckets 48 of the excavator conveyer. For this purpose I employ a special construction of cutter and a particular arrangement of the same on the excavator wheel as follows. Referring especially to Figs. 7 and 7^a, 8, 9 and 9^a each cutter comprises a substantially straight shank 57' and an outer terminal portion 57^a. The shank 57' extends outwardly from the outer face of the cutter carrying bar at substantially right angles thereto and rearwardly at a slight inclination, and the outer terminal portion 57^a is curved and extended inwardly in the direction of the central portion or section of the excavator wheel. The portion of the shank 57' extending beyond the outer face of the cutter carrying bar is sharpened and the outer terminal portion 57^a is sharpened to form a knife blade, and the said outer portion 57^a is extended rearwardly at a slight angle to the direction of movement of the same. The cutters are arranged at intervals along the cutter carrying bars to extend in spiral rows or series *b* and *c* around the conical side portions or sections of the excavator wheel as indicated by the lines *b* and *c* in Fig. 6 of the drawings.

In the operation of the excavator wheel the cutters 57 slice or shear the earth from the sloping side walls of the ditch in small

fragments or slices, the entire area of the side walls being uniformly acted upon by the cutters as they extend in spiral rows or series *b* (see Fig. 6), the line *b* indicating how the cutters of each spiral row *b* act successively to cover the entire area to be operated upon, the wheel traveling in the direction of the arrow. Owing to the particular arrangement of the cutter in spiral rows *c* and the particular construction of the cutters having the curved inwardly and rearwardly extending outer portions, they serve to feed or force the severed earth inwardly and downwardly to the bottom of the trench, the cutters cutting a thin slice and tipping or turning and moving the same inwardly toward the bottom of the ditch and in the path of the next succeeding cutter in the spiral row which operates in the same way, moving its slice with the other loose material thereupon inwardly. The curved outer portions 57^a of the cutters are located a sufficient distance from the frame work of the excavator wheel to provide ample space for the passage of the loosened material in its downward and inward movement to the buckets 48, and clogging of the cutters by the accumulation of the severed material at the side portions of the wheel is prevented.

The end hubs (see Fig. 4) 47 carry terminal cutters 58, which are of substantially the same construction and arrangement as the cutters 57 previously described and which have their straight shanks secured to the radial flanges 58' of the hubs with their terminal cutting portions or blades disposed in the same inclined plane as the cutting portions of the cutters 57 of the cutter carrying bars.

Now turning to Fig. 5 of the drawings, the excavator conveyer consists of a pair of spaced endless roller sprocket chains 60 and a plurality of excavating buckets secured to the chains at intervals between the same. The endless excavator conveyer is arranged to operate centrally of the excavator wheel, being trained thereover with the endless roller sprocket chains in engagement with sprocket teeth 61 on the central rims 43 of the excavator wheel and also arranged over a pair of front sprocket wheels 62 fixed on a transverse shaft 63 mounted for rotation in suitable bearings secured to the intermediate front inclined beams of the main frame 1 above and in advance of the excavator wheel. The excavator buckets, which are shown in the present instance as consisting of a continuously curved back and bottom 64 and end walls 65 are connected to opposite links of the sprocket chains 60 by transverse pivot shafts 66 arranged at the center of the arc or curvature of the back and bottom of the buckets. The buckets are provided with rearwardly extending arms 67 secured to the end walls thereof, and with brace members 130

68 extending over the rear ends of the said arms 67 to the bottom portion of the bucket. The rearwardly extending arms 67 are pivotally connected with short links 69, which 5 in turn are pivotally connected to the sprocket chains 60 to afford a flexible connection between the said arms and the chains for permitting the buckets to accommodate themselves to the changing positions of the 10 links of the sprocket chains in passing around the forward pair of sprocket wheels 62. Each bucket is provided at its front at opposite sides with curved laterally extending forwardly diverging wings 70, said 15 wings curving from top to bottom and being braced by members 71, the inner curved edges of the wings being secured to the end walls of the bucket which are cut away at the front to conform to the curvature of 20 the wings. The endless excavator conveyer is adapted to travel around the upper, rear and lower portion of the excavator wheel and the relative spacing of the buckets and cutter carrying bars is such that in passing 25 around the excavator wheel the buckets occupy a position substantially at the outer ends of the long cutter carrying bars. The buckets are provided at the front with straight transverse cutting edges 72, and the 30 wings 70 of the buckets have cutting edges 73 extending outwardly and upwardly. The wings act to direct the loose earth into the buckets and also serve to shape the lower portions of the sloping side walls of the 35 ditch to join the flat bottom of the ditch in a slight curve.

In order to insure the filling of the excavator buckets I also provide plows 74 (see particularly Figs. 10, 11, 12, 13 and 14 40 of the drawings) arranged in pairs at intervals on the excavator wheel to occupy a position intermediate the buckets as the buckets travel around the wheel, a pair of the plows working in advance of each bucket and serving 45 to direct the loose earth into the path thereof. The plows 74 are adjustably secured to the excavator wheel adjacent the central rims by brackets which have attaching portions or flanges 76 suitably secured 50 to the plows, and plates or flanges 77 arranged substantially at right angles to the attaching portions 76 and provided with inner curved slots 78 and an outer curved slot 79 through which pass bolts or other 55 suitable fastening devices for securing the brackets in place on the excavator wheel. The plows employed have the general characteristics of the common type of plow but they are disposed on the wheel in inverted 60 position.

Each plow 74 consists of a curved tapering share or blade having the cutting edges 80 and 80' terminating in a point 80², and said plows are adapted to be set, by adjusting the 65 brackets 75, at different angles to the line of

travel to suit the character of the soil being operated upon.

One stretch of the endless excavator conveyer extends upwardly and forwardly from the bottom of the excavator wheel to the 70 front pair of sprocket wheels and a top stretch or run extends rearwardly from the forward pair of sprocket wheels to the top of the excavator wheel passing over a transverse conveyer 81. The buckets traveling 75 upwardly and forwardly are adapted to carry the excavated material out of the ditch or trench and deliver the same to the transverse conveyer 81 and I provide means acting automatically to positively discharge the 80 material from the buckets, said means including an ejector 82 for each bucket and fixed cams 83. Each ejector 82 consists of a blade 84 hinged between the ends of the bucket upon the transverse pivot shaft 66, 85 which connects the bucket to the conveyer chain, and an outer portion 85 rigid with the blade 84 and extending at substantially right angles thereto from the said blade at its pivot point. The outer ends of the blade 90 and portions 85 are connected by a brace 86, and the outer projecting portion 85 has lateral projections 87 provided with anti-friction rollers 88. The blade 84 is of a size to extend from the transverse pivot shaft 66 to 95 within close proximity to the inner concave face of the curved back and bottom of the bucket and is adapted to work within the bucket to discharge the contents and to clean and scrape the interior of the bucket in its 100 oscillatory movement on the pivot shaft 66. When the buckets occupy an upright horizontal position their ejector blades 84 extend vertically at the front thereof, the said blades changing their position by gravity 105 within the buckets as the angular position of the buckets change when carried around by the conveyer. The blades are forced rearwardly by the material as the buckets fill, the rearward movement of the blades 84 being 110 limited by stops 88' extending inwardly from the attaching portions of the rearwardly extending arms 67 at the top of the buckets. When the bucket is filled the blade 84 of the ejector is held against the stops 115 88' by the material, the blade 84 constituting the top of the bucket while the same is traveling up the front inclined stretch of the conveyer and until the bucket passes around the front pair of sprocket wheels and is inverted, which brings the ejector blade 84 at the bottom side of the bucket while the bucket is moving rearwardly to a position over the transverse conveyer. When the buckets approach a point above the transverse conveyer, the ejector is oscillated or swung through the bucket to discharge the material therefrom onto the transverse conveyer, the laterally extending portions of the outer blade 85 of the ejector engaging the 120 130

cams 83, which retards the forward travel of the outer end of the blade 85 and causes a swinging or oscillatory movement of the ejector blade 84 through the bucket. The 5 cams 83 which are suitably fixed to the frame 1 in position at opposite sides of the conveyer comprise straight portions 89 which are inclined slightly to the rear, upper curved portions 90, and a rearwardly extending horizontal portion 91. The rollers 88 of the laterally extending portions of the outer blade 85 ride downwardly on the inclined portions 89 of the cams passing around the lower ends of the same and from thence up 10 inclined guides 92 which extend upwardly from points in rear of the lower terminals of the inclined portions 89 to horizontal tracks 93. 94 designate horizontal tracks supporting the upper stretch of the conveyer 15 and the horizontal tracks 93 which are substantially the same length as the tracks 94, serve to support the ejectors with their blades 84 at the front of the buckets. As soon as the rollers of the laterally projecting 20 portions 87 leave the tracks 93 the ejector oscillates by gravity on its pivot and in this movement serves to scrape or free the interior of the bucket from any material clinging thereto. If any of the buckets should be 25 empty when traveling over the front upper stretch of the excavating conveyer past the cams, the rollers of the laterally projecting portions, since the ejector blade is not held in its outermost position by the material as 30 when the buckets are filled, instead of riding downwardly on the inclined portion 89 of the cams, they ride upwardly over the curved portions 90 of the cams and from thence to the horizontal tracks 93. The transverse 35 conveyer 81, which is adapted to convey the excavated material to one side of the ditch or trench, comprises an inner stub section 95 and an outer pivoted section, a portion of the frame 95^a of which and the point of its 40 connection being shown to the right of Fig. 3 of the drawings, said pivoted section being of any of the well known or conventional constructions, the latter being of conventional form and not shown in detail in the drawings. 45 The inner conveyer section 95 comprises a frame 96 having rollers 97-98 at opposite ends thereof, and series of intermediate rollers 99 arranged in angular relation to support the conveyer belt 98' in curved 50 form as shown. The inner conveyer section 95 is pivotally connected at its front to the main frame by transverse pivots 100 suitably connected to the front outer inclined beams of the main frame, and said conveyer frame 55 is supported at its rear by a pair of oppositely disposed link members 101, pivotally connected at their upper ends to the conveyer frame at the rear thereof and each pivotally connected at its lower end to one of 60 the tractor frames at 102. This particular 65

connection of the conveyer frame with the tiltable main frame and the tractor frames provides means for supporting the conveyer frame in horizontal position and for maintaining the same in such position irrespective 70 of the vertical adjustment of the main frame on its pivot.

Extending along the rear side of the inner conveyer section is an apron which extends upwardly at an inclination from the conveyer and serves to direct material which may fall to one side of the conveyer onto the conveyer. The apron is connected at its upper end to the main frame, and at its lower end to the conveyer frame, the apron 75 being extensible to accommodate for the change in the relative position of the parts when the main frame is adjusted vertically. The apron comprises an upper flexible portion 95' constructed of canvas or the like and 80 a lower substantially rigid portion 96' in the form of a plate preferably of sheet metal. The upper portion 95' is secured to and wound upon a spring roller 104 suitably mounted in bearings secured to the horizontal 85 track portions 93 and is suitably connected at its lower end with the rigid lower portion 96', the latter being provided with hook portion 106 adapted to detachably engage a transverse rod 107 which is supported in 90 brackets 107' secured to the conveyer frame. The spring roller places the apron under tension serving to maintain the same always substantially taut, the upper flexible portion of the apron unwinding from the 95 spring roller and being wound up thereon as the relative position of the parts change when the main frame is raised or lowered.

Any suitable means may be employed for supplying power for actuating the excavator mechanism, and to the tractors and hoisting drums but I prefer to employ an engine 108 of the internal combustion type.

Referring to Figs. 2 and 3 the engine is suitably mounted on the main frame preferably at the front thereof. 109 designates the engine shaft and 110 is the main drive shaft mounted on the main frame 1 and extending transversely in alignment with the engine shaft, with which it is adapted to be 115 coupled by a reversing clutch 111.

The tractors are provided with drive gear connections including large sprocket wheels 112 at the outer ends of the front sprocket wheel shafts 12, transverse shafts 113 provided with sprocket wheels 114 and 115 at opposite ends thereof, sprocket chains 116 connecting the sprocket wheels 112 with the sprocket wheels 114, and sprocket chains 117 connecting the sprocket wheels 115 with 120 sprocket wheels 118 at opposite ends of a main tractor drive shaft 119 suitably mounted on and extending transversely of the main frame 1. Power is adapted to be 125 transmitted to the shaft 119 from the main

drive 110 through an intermediate shaft 120, which has sprocket wheels 121 and 122 at opposite ends thereof that are geared respectively by sprocket chains 123 and 124 with 5 a sprocket wheel 125 on the main drive shaft 110, and a sprocket wheel 126 on the main tractor drive shaft 119. This affords a more direct drive from the main drive shaft 110 to the tractors in transporting the machine 10 from place to place. In order to provide for steering the machine, the main tractor drive shaft 119 is divided at its central portion and the sprocket wheel 126 is mounted loosely on the said shaft at the divided portion 15 thereof and provided with clutch faces at opposite sides thereof to coöperate with clutch members 127 and 128 feathered respectively on the adjacent inner ends of the two parts of the shaft. Suitable hand levers 127' and 128' are provided for the said clutches and by operating the clutches the tractors can be driven independently of each other.

I also provide for transmitting power to 25 the tractors to gradually advance the machine during the excavating operation in accordance with the work performed by the excavating mechanism. 129 designates a counter shaft arranged parallel with the 30 main drive shaft 110 and adapted to receive motion from the main drive shaft through a reducing gear 130, which is adapted to be operatively connected to the main drive shaft 110 by a clutch 131. Power is 35 adapted to be transmitted from the counter shaft to the intermediate shaft 120 by eccentrics 132 and 132' and lever and ratchet gears 133 and 134, the levers of the ratchet gears being suitably connected with the eccentrics 40 and the eccentrics being disposed on the shaft whereby the levers of the ratchet gears are moved alternately forward and back to transmit a continuous rotary motion to the intermediate shaft.

45 The sprocket wheel 125 on the main drive shaft 110 is loosely mounted and adapted to be clutched to the shaft by the clutch 131, said clutch serving to alternately connect the shaft with said sprocket wheel 125 to 50 obtain a direct drive, and to operatively connect the shaft with the reducing gear 130. The lever and ratchet gears 133 and 134 are provided with clutches 135 and 136 to clutch the same to the intermediate shaft 120, said 55 clutches being operated to unclutch the gears 133 and 134 from the shaft when the clutch 131 is shifted to obtain the direct drive.

The transverse shafts 113 are mounted at 60 the front portion of the tractor frames in axial alinement with the pivotal axes of the main frame 1, whereby when the main frame is swung vertically, the same spaced relation is maintained between the sprocket wheels 118 and the sprocket wheels 114 and 115 and 65 these gear connections are not affected.

Power is transmitted to the excavating mechanism and the belt of the transverse conveyer 81 from the counter shaft by a sprocket chain 137 connecting sprocket wheel 138 fixedly secured to the counter shaft, and 70 a sprocket wheel 139 on the sprocket wheel shaft 63.

The end rollers 97-98 of the inner section of the transverse conveyer are provided with beveled pinions 140 which mesh with 75 bevel pinions 141 on the outer ends of the short shaft 142, which at their inner ends have small sprocket wheels 143 that are connected by sprocket chains 144 with outer sprocket wheels 145 fixed on the shaft 63. 80

The hoisting drums 37 are mounted at opposite sides of the main frame 1 on a drum shaft 150, which extends across the frame and is suitably mounted thereon, the drums 37 being fixed to the shaft to rotate therewith. Power is transmitted to the drum shaft 150 from the engine shaft through a shaft 151 connected with the engine shaft by a sprocket chain 152 gearing with sprocket wheel 153 on shaft 151 and a sprocket wheel 90 155 on the engine shaft. On the drum shaft is fixed a worm gear wheel 156 meshing with a worm shaft 157 that has a beveled pinion 158, which meshes with beveled pinions 159 and 160 loosely mounted on the shaft. The 95 beveled pinions 159 and 160 are provided with an intermediate clutch whereby either of said gears may be caused to turn the worm shaft and means afforded for rotating the shaft in reverse directions to raise or 100 lower the main frame as desired, the worm gear serving as a lock for the drum shaft when power is not being applied thereto.

A rocker shaft 162 is connected in any suitable way to the intermediate clutch to 105 actuate the same, and cables 162' are secured to opposite arms 163 of the rocker shaft and extend to opposite sides of the machine to hand levers 164 mounted on the tractor frames at the rear thereof, whereby the clutch 110 can be conveniently controlled from these points. The hand levers 164, which are pivoted to the tractor frames are provided with short arms 165 to which the outer stretches 115 of the cables are secured.

167 designates a drum adapted to be employed to raise and lower the outer pivoted section of the transverse conveyer. A worm gear 167, reversing gears 168 and 169, and a clutch for the drum are provided similar to 120 that provided for the hoisting drums 37, hereinbefore described, except that in this instance the drum is loosely mounted on the drum shaft and is controlled by a lever 170 mounted at the front of the main frame. 125

The drawings illustrate a preferred embodiment of the invention and it will be understood that minor changes in the particular construction, combination and arrangement of parts shown may be made 130

without departing from the broad principle of the invention, the scope of which is defined in the appended claims.

What I claim is:

- 5 1. An excavating machine including a rotary excavator wheel having a conical side portion provided with cutters to make a side wall of the ditch inclined, said cutters having means to force the loose material to one 65 side of the line of travel thereof downwardly and inwardly toward the bottom of the ditch.
- 10 2. An excavating machine including a rotary excavator wheel having a conical side portion provided with cutters to make a side wall of the ditch inclined, the cutters having means to force the loose material to one side of the line of travel thereof downwardly and inwardly toward the bottom of the ditch, 70 said cutters being disposed on the conical side portion of the wheel to extend in spiral rows thereover.
- 15 3. An excavating machine including a rotary excavator wheel having a conical side portion provided with cutters to make a side wall of the ditch inclined, said cutters having means to force the loose material to one side of the line of travel thereof downwardly and inwardly toward the bottom of the ditch, 75 said cutters being disposed on the conical side portion of the wheel to extend in spiral rows thereover.
- 20 4. An excavating machine including a rotary excavator wheel having a conical side portion provided with cutters to make a side wall of the ditch inclined, said cutters having means to force the loose material to one side of the line of travel thereof downwardly and inwardly toward the bottom of the ditch, 80 and inwardly toward the bottom of the ditch, a conveyer operating at the base of the conical side portion of the wheel to convey the loose material from the bottom of the ditch, the conveyer being provided with 85 buckets to receive the excavated material, said buckets having laterally extending wings arranged to gather and direct the loose material within the buckets.
- 25 5. An excavating machine including a rotary excavator wheel having a conical side portion provided with cutters to make a side wall of the ditch inclined, said cutters having means to force the loose material to one side of the line of travel thereof downwardly and inwardly toward the bottom of the ditch, 90 and inwardly toward the bottom of the ditch, a conveyer operating at the base of the conical side portion of the wheel to convey the loose material from the bottom of the ditch, the conveyer being provided with buckets to receive the excavated material, and plows on the excavator wheel adjacent the base of the conical side portion and arranged to operate between the buckets of the conveyer.
6. An excavating machine including a rotary excavator wheel having a conical side portion provided with cutters arranged to make a side wall of the ditch inclined, said cutters comprising a shank extending outwardly from the conical side portion and an outer cutting portion spaced from the conical side portion and extending laterally and rearwardly at an angle to the shank portion. 95
7. An excavating machine including a rotary excavator wheel having a conical side portion provided with cutters to make a side wall of the ditch inclined, said cutters having substantially flat blade sections inclined inwardly toward the base of the conical side portion of the wheel. 100
8. An excavating machine including a rotary excavator wheel having a conical side portion provided with cutters arranged to make a side wall of the ditch inclined, each of said cutters having cutting portions spaced from the conical side portion of the wheel, and extending inwardly toward the base of the conical portion and also extending rearwardly at an angle to the line of travel of the cutters. 105
9. An excavating machine including a rotary excavator wheel having a conical side portion provided with cutters to make a side wall of the ditch inclined, each of said cutters comprising a shank portion extending outwardly from the conical side portion of the wheel, and an outer substantially flat blade portion curving inwardly from the said shank portion toward the base of the conical portion of the wheel. 110
10. An excavating machine including a rotary excavator wheel having a conical side portion provided with cutters to make a side wall of the ditch inclined, the cutters being disposed on the conical side portion to extend in spiral rows thereover, each of said cutters having a cutting portion spaced from the conical side portion of the wheel, and extending inwardly toward the base of the conical side portion, and also extending rearwardly at an angle to the line of travel of the cutters. 115
11. An excavating machine including a rotary excavator wheel having a conical side portion provided with cutters to make a side wall of the ditch inclined, each of said cutters comprising straight shanks extending outwardly from the conical side portion, and an outer curved portion extending inwardly and rearwardly toward the base of the conical portion. 120
12. An excavating machine including a rotary excavating wheel having a conical side portion provided with cutters to make a side wall of the ditch inclined, each of said cutters comprising straight shanks extending outwardly from the conical side portion at substantially right angles there-

to, and an outer curved cutting portion extending inwardly and rearwardly toward the base of the conical portion.

13. An excavating machine including a rotary excavator wheel having conical side portions provided with cutters to make the side walls of the ditch inclined and having means to feed the loose material downwardly and inwardly toward the bottom of the ditch, and a conveyer operating centrally of the wheel to convey the loose material upwardly from the bottom of the ditch, said conveyer having buckets to receive the excavated material, said buckets being provided with laterally extending wings at the front thereof arranged to gather and direct the loose material within the buckets.

14. An excavating machine including a rotary excavator wheel having conical side portions provided with cutters to make the side walls of the ditch inclined and having means to feed the loose material downwardly and inwardly toward the bottom of the ditch, and a conveyer operating centrally of the excavator wheel to convey the loose material upwardly from the bottom of the ditch, and plows mounted centrally of the wheel to direct the material in the path of the conveyer.

15. An excavating machine including a rotary excavator wheel having conical side

portions provided with cutters to make the side walls of the ditch inclined and having means to feed the loose material downwardly and inwardly toward the bottom of the ditch, and a conveyer operating centrally of the excavator wheel and having buckets to convey the loose material upwardly from the bottom of the ditch, and plows at the central portion of the wheel disposed in inverted position to operate in advance of the buckets.

16. An excavating machine including a rotary excavator wheel having conical side portions provided with cutters to make the side walls of the ditch inclined and having means to feed the loose material downwardly and inwardly toward the bottom of the ditch, a conveyer operating centrally of the excavator wheel and having buckets to convey the loose material upwardly from the bottom of the ditch, and plows arranged in pairs mounted at the central portion of the wheel to operate between the buckets to direct the excavated material within the path of the same.

In testimony whereof I hereunto affix my signature in the presence of two witnesses.

ELLSWORTH A. DEWEY.
